UNITED STATES PATENT OFFICE.

JOHN BIRKENHEAD, OF MANSFIELD, MASSACHUSETTS.

LATHE.

SPECIFICATION forming part of Letters Patent No. 272,849, dated February 27, 1883.

Application filed October 10, 1882. (No model.)

To all whom it may concern:

Be it known that I, JOHN BIRKENHEAD, of Mansfield, in the county of Bristol, of the State of Massachusetts, have invented a new and useful Improvement in Lathes; and I do hereby declare the same to be described in the following specification and represented in the accompanying drawings, of which—

Figure 1 is a front elevation, and Fig. 2 an end view, of a lathe provided with my invention, the nature of which is defined in the claims hereinafter set forth. Fig. 3 is a vertical section taken on the line *a b* of Fig. 1. Fig. 4 is a view of the mechanism applied to the tool-carriage and its feeding-shaft thereof.

My said invention may be said to be a "stop motion" for the tool-carriage, the purpose of it being mainly to arrest the feeding or lateral movement of the said carriage at any desirable position of its traverse, as occasion may require.

In the drawings, *A* denotes the lathe bed or frame; *B C*, the puppets; *D*, the tool-carriage, the latter resting upon the bed or being adapted to it in the usual manner.

E is the feeding-shaft of the tool-carriage, such shaft being grooved lengthwise, as shown at *e*, and supported in bearings *d e*, so as not only to be capable of revolving, but of moving lengthwise of it in them. In the bearing *e* there is applied thereto and to the shaft a spring, *f*, for retracting the shaft.

The driving-shaft of the feeding mechanism of the lathe is shown at *g*, which shaft and the mandrel are provided with sets of cone-pulleys *h* and *i*, about which an endless band is to run to give rotary motion from the mandrel. The shaft *g* is tubular, and is sustained by and revolves on a shaft, *g'*, which is fixed to and projects from an arm, *h'*. (See Fig. 3.) Said arm encompasses and turns upon the bearing *d*, and is provided with ears *i' i''* and a screw, *k*, the whole being as shown in Fig. 3, so as to enable the arm to be turned on the bearing and clamped thereto, in order to admit of depression of the shaft *g*, to effect, as occasion may require, the tightening of the endless band of the cone-pulleys. Fixed on the shaft *g* is a pinion, *l*, that engages with a gear, *m*, fixed on the shaft *E*. A housing, *n*, fastened to the arm *h'*, extends over the gears *m* and *l*.

From the above it will be seen that the rotary motion of the shaft *E* is occasioned by the

gears *l* and *m* when the gear *l* is put in revolution with and by the shaft *g*. It will also be seen that on the shaft *E* being moved to the left far enough in its bearings its gear *m* will be thrown out of engagement with the pinion *l*, and thereby rotary motion of such shaft *E* will be stopped, in which case the lateral movement of the tool-carriage will be arrested.

On the shaft *E* there is arranged concentrically a worm or screw, *F*, so applied to said shaft that it will revolve with and at the same time slide upon it. The worm is disposed within an oil cup or reservoir, *R*, the ends of which abut against the ends of the worm, said reservoir being secured to the part *p* of the tool-carriage, a ring, *G*, encompassing the shaft *E* and adapted to it, so as to be capable of being moved on it lengthwise of it, provided with a clamp-screw, *q*, to fix it in place on the shaft. Furthermore, there is to the part *p* a projection, *r*, which extends backward therefrom in range with the ring *G*, and there projects from the lathe-bed a toothed rack, *s*, which engages with a pinion, *t*, such pinion being supported on a journal, *u*, sustained by the part *p*. The pinion *t* engages with a gear, *v*, turning on a fixed journal. On another fixed journal, *x*, supported by the part *p*, is a worm-gear, *y*, that engages with the worm *F*, and is provided with the spur-gear *z*.

Fulcrumed on the journal *x* is a rocker-lever, *a'*, from which a handle, *b'*, extends through a slot, *c'*, in the part *p*. This lever carries upon journals *c' d'*, projecting from it, two gears, *e' f'*, either of which, by means of the lever, can be thrown either out of or into engagement with the gear *v*. The gear *e'* engages with the gear *z* and the gear *f'* with the gear *e'*, and when either of the gears *e' f'* is in engagement with the gear *v* the other is out of engagement therewith. While one of the gears *e' f'* is in engagement with the gear *v*, the tool-carriage will be moved laterally in one direction, it being moved in the opposite direction when the other of said gears *e' f'* is in engagement with the gear *v*.

If, while the tool-carriage is being moved in a direction to the left, we may desire to stop it, when it may attain any position within the extent of its traverse, we move the ring *G* to the right position on the shaft *E* and clamp such ring to the shaft. On the projection *r* being carried by the carriage into contact with the

ring, the shaft E will be moved endwise in its bearings with the carriage until the gear m is moved out of engagement with the gear l. On such disengagement of the said two gears l and m taking place, the stoppage of the carriage results.

- On the shaft u is a crank, w. On turning the lever a' so as to throw both gears e' and f' out of engagement with the gear v, and afterward revolving the crank w the right way, the carriage will be moved so as to allow the spring f to retract the shaft E to carry the gear m back into engagement with the gear l, after which further motion of the carriage in the same direction may be produced by moving the lever a' so as to throw into engagement with the gear v the proper one of the two gears e' f'. What I claim as my invention is as follows, *viz*:
- 1. The combination of the projection r of the tool-carriage, and the adjustable ring G, and its clamping-screw applied to the worm-shaft, and

the retractor-spring f, adapted to such shaft, and the lathe-bed, substantially as set forth, with mechanism, essentially as explained, for imparting traverse motions to the said tool-carriage, such mechanism consisting of the driving-shaft g, gears l m, shaft E, worm F, lever a', gears y, z, e', f', v, and t, and the toothed rack s, all being arranged and adapted and to operate essentially as set forth.

2. The combination of the arm h', adapted to the bearing d of the worm-shaft E, and clamping device, as described, with said bearing and with the shaft g of the driving-gear l, arranged and operating substantially as and for the purpose set forth.

3. Jointly with the bearing d, the arm h', and the gear-wheels, the housing n, as and for the purpose set forth.

JOHN BIRKENHEAD.
